UNITED STATES PATENT OFFICE

133,941

DESIGN FOR A TYPEWRITING MACHINE

William J. O'Neil, Atlantic Beach, N. Y., assignor to Underwood Elliott Fisher Company, New York, N. Y., a corporation of Delaware

Application January 20, 1942, Serial No. 105,335

Term of patent 14 years

To all whom it may concern:

Be it known that I, William J. O'Neil, a citizen of the United States, residing in Atlantic Beach,
in the county of Nassau and State of New York,
have invented a new, original, and ornamental Design for a Typewriting Machine, of which the following is a specification, reference being had to the accompanying drawings, forming part thereof.

Figure 1 is a front perspective view of a typewriting machine showing my design from the right-hand side thereof.

writing machine shown in Figure 1, the view being from the left-hand side thereof.

The dominant features of my design reside
in the portion of the machine shown in solid lines.

I claim:

The ornamental design for a typewriting machine, as shown and described.

WILLIAM J. O'NEIL.
